CLAIM

The ornamental design for a model vehicle suspension arm as shown and described.

DESCRIPTION

FIG. 1 is an upper, left, front perspective view of a model vehicle suspension arm showing our new design;

FIG. 2 is an upper, right, rear perspective view thereof;

FIG. 3 is a lower, right, front perspective view thereof;

FIG. 4 is a lower, left, rear perspective view thereof;

FIG. 5 is a front elevation view thereof;

FIG. 6 is a rear elevation view thereof;

FIG. 7 is an upper plan view thereof;

FIG. 8 is a lower plan view thereof;

FIG. 9 is a right-side elevation view thereof; and,

FIG. 10 is a left-side elevation view of a model vehicle suspension arm.

In the drawings, the broken lines illustrate portions of the model vehicle suspension arm that form no part of the claimed design.

Only the left-side model vehicle suspension arm is shown. The right-side model vehicle suspension arm is a mirror image of the shown model vehicle suspension arm.
